PIPE RACK

Domenico Patriarca, Providence, R. I.

Application January 3, 1955, Serial No. 33,792

Term of patent 14 years

(Cl. D80—9)

Fig. 1

Fig. 2

Fig. 1 is a plan view of a pipe rack embodying my new design;

Fig. 2 is an elevation thereof.

The broken lines shown in Fig. 2 are for illustrative purposes only.

I claim:

The ornamental design for a pipe rack, as shown and described.
